UNITED STATES PATENT OFFICE

131,288

DESIGN FOR A TIE CLASP

Rhea J. Vernon, Abilene, Tex.

Application July 12, 1941, Serial No. 102,107

Term of patent 7 years

To all whom it may concern:

Be it known that I, Rhea J. Vernon, citizen of the United States, residing at Abilene, in the county of Taylor and State of Texas, have invented a new, original, and ornamental Design for a Tie Clasp, of which the following is a specification, reference being had to the accompanying drawing, forming part thereof.

Figure 1 is a perspective view of a tie clasp showing my new design, the letter V being merely representative.

Figure 2 is a front elevation of the tie clasp;
Figure 3 is a plan view;
Figure 4 is an end elevational view of the same.

The essential feature of my design resides in the placement of a three dimensional initial letter on the end of the tie clasp and in a plane perpendicular to the front of the clasp.

I claim:

The ornamental design for a tie clasp, as shown and described.

RHEA J. VERNON.
